UNITED STATES PATENT OFFICE.

HARRY E. WOLFE, OF HASTINGS, MICHIGAN.

COMBINATION FOUNDRY-TOOL.

1,391,814.

Specification of Letters Patent. Patented Sept. 27, 1921.

Application filed April 20, 1921. Serial No. 462,867.

To all whom it may concern:

Be it known that I, HARRY E. WOLFE, a citizen of the United States of America, and resident of Hastings, in the county of Barry 5 and State of Michigan, have invented certain new and useful Improvements in Combination Foundry-Tools, of which the following is a specification.

This invention relates to combination 10 tools, and particularly to a combined shovel and tamping device, the said invention being primarily for use in foundries where sand is to be delivered to molds and the sand is to be tamped, as in the molding operation.

15 An object of this invention is to provide a novel tamping attachment having adjustable features which permit the tamping device to be used edgewise or flat for peening sand along the sides of the mold or for 20 tamping it in the middle thereof.

A further object of this invention is to produce a tamping device capable of being held in one position of adjustment and then released to assume another position where it 25 will operate in a different manner from that in which it operated in the first position.

A still further object of this invention is to produce an attachment for shovel handles 30 in which the adjustment may be readily attained, and having a securing device which will positively retain the parts in one position of adjustment.

With the foregoing and other objects in view, the invention consists in the details of 35 construction, and in the arrangement and combination of parts to be hereinafter more fully set forth and claimed.

In describing the invention in detail, reference will be had to the accompanying 40 drawings forming part of this application wherein like characters denote corresponding parts in the several views, and in which—

Figure 1 illustrates a view in elevation of 45 a shovel, showing the device embodying the invention partly in section, applied thereto;

Fig. 2 illustrates an edge elevation of the supplemental handle;

Fig. 3 illustrates a central sectional view 50 thereof;

Fig. 4 illustrates a perspective view of a locking device; and

Fig. 5 illustrates a perspective view of an element coacting therewith.

55 In these drawings, 10 denotes a shovel and 11 a handle, which may be of any ordinary

construction. The supplemental handle comprises a hollow shank member 12 secured to the handle 11 by a fastening 13, such as a rivet, and the said supplemental handle 60 has an elongated channel 15 preferably closed by a face plate 16, the said channel constituting a seat in which the latch 17 is slideable. The latch 17 has a rod 18 connected to its inner end, and the said rod extends outwardly, as shown at 19, through a slot 20 and terminates in a thumb piece 21 which may be pressed to retract the latch 17 against the action of a spring 22 which encircles the rod 18 between the inner end 65 of the latch and an abutment 23 which acts as a guide for the rod and as a limiting element for holding the spring under compression. The outer end of the handle terminates in arms 24 and 25 between which 70 a pivot or pintle 26 extends, and the said arms 24 and 25 have lugs 27 and 28 respectively, which engage the tamping head 29 to limit the swinging movement of the head in one direction, it being shown in the drawing 75 that the side of the tamping head has recessed portions such as 30 forming seats for the lugs, and the edge of the said tamping head has an opening or recess 31 in which the end of the latch projects. The latch 80 prevents the movement of the tamping head in one direction and the lugs engaging the side of the tamping head prevent it from moving in the opposite direction, and hence, so long as the latch is lying in the recess 85 31 of the tamping head, the tamping head 90 will be held against movement.

The tamping head furthermore has one edge 32 of a contour which will prove effective in packing sand around the edges of a 95 mold, but when the tamping head is released and extends across the end of the handle as shown in dotted lines (Fig. 3), the effective area is relatively large and hence, sand in the middle of a mold may be tamped expeditiously.

In order to rotatably mount the tamping head on the pivot 26, a bushing 35 is inserted in a tubular portion 34 of the tamping head and the tamping head rotates on the 105 bushing, and the said bushing is held against rotation with relation to the pivot. The bushing 35 is rotatably mounted on the pivot but it has a lug 36 which locks into a recess 37 in the arm 24 of the handle. 110

A spring 38 has one end anchored to the bushing 33 and another end anchored to the

bushing 35, and hence, when the tamping head swings with relation to the pivot 26 to the position shown in Fig. 1, the spring is wound and is under tension when the lug 36 is applied to the arm 24. When the bushing 35 is moved axially of the pivot and the lug 36 disengages from the arm 24, the spring will prove effective to swing the tamping head to the dotted line position shown in Fig. 3, when the device will be operative to form a butt which will be used in ramming the top of the mold, and when further handling the shovel, it comes natural to return the tamping head to the position shown in Fig. 1 when it will again be caught by the latch and retained until released.

The tamping head has lugs or bumpers 39 which come into engagement with the lugs 28 when the tamping head is in a horizontal position and this serves to prevent undue oscillation of the tamping head.

The tubular portion 34 has a bushing 33 applied to it, and the said bushing 33 has a flat side 33^a which fits against a corresponding flat side of the tube, in order that the tube and bushing 33 may rotate together on the pintle 26, and it is by reason of the fact that the bushing 35 is held stationary while the bushing 33 is being rotated, that the spring 38 is wound.

I claim:

1. In a combined shovel and tamping tool, a shovel having a handle, a hollow shank applied to the handle of the shovel and terminating in diverging arms, a latch slidable with relation to the arms and adapted to project therebetween, a tamping head rotatably mounted between the said arms and having means for engaging the latch, and a resilient member for turning the tamping head on its pivot.

2. In a combined shovel and tamping tool, a shovel having a handle, a tamping tool applied thereto consisting of a hollow shank, diverging arms at the outer end of the shank, a pivot supported by the arms, a tamping head rotatably mounted on the pivot, a latch in the shank projecting from the edge thereof and adapted to hold the tamping head in one position of adjustment, and a resilient member for turning the tamping head on its pivot.

3. In a combined shovel and tamping tool, a shovel having a handle, a tamping tool applied thereto consisting of a hollow shank, diverging arms at the outer end of the shank, a pivot supported by the arms, a tamping head rotatably mounted on the pivot, a latch in the shank projecting from the edge thereof and adapted to hold the tamping head in one position of adjustment, a resilient member for turning the tamping head on its pivot, a bushing on the pivot connected to the tamping head, a bushing slidable on the pivot and supporting the tamping head, and means for holding one of the bushings in adjusted position with relation to one of the arms.

4. In a device for tamping sand, a shank having diverging arms and lugs extending inwardly from the sides thereof, a latch slidable in the shank and projecting therefrom, a pivot, a tamping head rotatably mounted on the pivot between the arms and engaging the lugs for limiting its movement, the said tamping head having a latch engaging portion whereby the said tamping head is held at one position of adjustment, and means for partially rotating the tamping head on the pivot when the latch is released.

HARRY E. WOLFE.
